(57) **CLAIM**

The ornamental design for a vehicle seat pocket organizer assembly, as shown and described.

DESCRIPTION

FIG. 1 is a perspective top front right view of a vehicle seat pocket organizer assembly, including a case element, a pair

of auxiliary case elements, a first insert element, and a second insert element, showing my new design;

FIG. 2 is a perspective top front right view of the case element;

FIG. 3 is a perspective top rear left view of the case element;

FIG. 4 is a front elevation view of the case element;

FIG. 5 is a rear elevation view of the case element;

FIG. 6 is a left elevation view of the case element;

FIG. 7 is a right elevation view of the case element;

FIG. 8 is a top plan view of the case element;

FIG. 9 is a bottom plan view of the case element;

FIG. 10 is a perspective top front right view of an individual auxiliary case element;

FIG. 11 is a perspective top rear left view of an individual auxiliary case element;

FIG. 12 is a front elevation view of an individual auxiliary case element;

FIG. 13 is a rear elevation view of an individual auxiliary case element;

FIG. 14 is a left elevation view of an individual auxiliary case element;

FIG. 15 is a right elevation view of an individual auxiliary case element;

FIG. 16 is a top plan view of an individual auxiliary case element;

FIG. 17 is a bottom plan view of an individual auxiliary case element;

FIG. 18 is a perspective top front right view of the first insert element;

FIG. 19 is a perspective top rear left view of the first insert element;

FIG. 20 is a front elevation view of the first insert element;

FIG. 21 is a rear elevation view of the first insert element;

FIG. 22 is a left elevation view of the first insert element;

FIG. 23 is a right elevation view of the first insert element;

FIG. 24 is a top plan view of the first insert element;

FIG. 25 is a bottom plan view of the first insert element;

FIG. 26 is a perspective top front right view of the second insert element;

FIG. 27 is a perspective top rear left view of the second insert element;

FIG. 28 is a front elevation view of the second insert element;

FIG. 29 is a rear elevation view of the second insert element;

(Continued)

FIG. 30 is a left elevation view of the second insert element; FIG. 31 is a right elevation view of the second insert element; FIG. 32 is a top plan view of the second insert element; and, FIG. 33 is a bottom plan view of the second insert element. The broken lines define the bounds of the claimed design and form no part thereof.
